(57) **CLAIM**

The ornamental design for a rear air diffuser for motor vehicle as shown and described.

DESCRIPTION

FIG. 1 is a perspective view of a rear air diffuser for motor vehicle showing my new design;

FIG. 2 is a front view thereof;

FIG. 3 is a rear view thereof;

FIG. 4 is a right-side view thereof, the left side being a mirror image thereof;

FIG. 5 is a top view thereof; and,

FIG. 6 is a bottom view thereof.

The darker and lighter grey tones indicate a contrast in appearance.

1 Claim, 6 Drawing Sheets
